United States Patent Office

Des. 190,057
Patented Apr. 4, 1961

190,057

BOTTLE OR SIMILAR ARTICLE

Morris Gottsegen, Beverly Hills, Calif., assignor to Gotham Industries, Inc., New York, N.Y., a corporation of New York

Filed Apr. 21, 1960, Ser. No. 60,276

Term of patent 14 years

(Cl. D58—6)

Figure 1 is a perspective view of a bottle embodying
my new design;

Figure 2 is a front elevational view thereof;

and

I claim:

The ornamental design for a bottle or similar article,
as shown.
